UNITED STATES PATENT OFFICE.

JOSEPH WALWYN WHITE, OF WIDNES, ENGLAND.

APPARATUS FOR RAISING SUNKEN VESSELS AND OTHER BODIES.

1,200,404.

Specification of Letters Patent.

Patented Oct. 3, 1916.

Application filed July 17, 1916. Serial No. 109,802.

To all whom it may concern:

Be it known that I, JOSEPH WALWYN WHITE, a subject of the King of Great Britain, residing in Widnes, in the county of 5 Lancaster, in the Kingdom of England, have invented certain new and useful Improvements in Apparatus for Raising Sunken Vessels and other Bodies, of which the following is a specification.

10 Several schemes at different times have been brought forward for placing one or more pontoons over a ship, placing cranes thereon with their chains or ropes passing through holes in the pontoons, and applying 15 one or more large magnets to the ends of the chains, but all these have resulted in failure owing to the following causes. It is found impracticable to carry above 25 tons on any one magnet, and therefore a very 20 large number of magnets have to be employed each practically on a separate chain, though in some circumstances two, three, four, or even more magnets may be by compensating devices used on a single chain 25 or rope. Now this invention is designed to raise any ship and to use a very large number of magnets without them interfering with each other.

The invention is best set forth by aid of 30 the accompanying drawings, in which,

Figure 1 shows my device in diagrammatic form, being a cross section of the apparatus in operation. Fig. 2 is a longitudinal view of the same, and Fig. 3 is a perspective view 35 of a compensating device whereby four magnets can be attached to one chain, and all pull equally.

In these, A is a pair of pontoons or even a couple of vessels attached together by a 40 stout bridge or deck B. On this deck are rows of equalizing hydraulic rams C C, extending the whole length of the ship, and a sufficient distance across the bridge to cover the wreck to be raised. It will be seen 45 in the drawings that there are 55 of these rams, but in practice I may have many more, as each ram preferably is made to carry a load of 80 tons or so, so that with an 8000 ton boat for instance, about 100 50 of these rams would be required.

D D are winding winches and E E store pulleys or drums for carrying the wire lifting ropes when wound up.

K K are a series of wire ropes, each carrying at one end an electro-magnet F. This electro-magnet is only put in diagrammatic

form, but of course consists of a soft steel or iron magnet surrounded with powerful insulated coils of wire to convert them into electro-magnets in the usual manner, the insulated electric wire passing preferably through the center of the raising rope or otherwise, to electrical storage batteries or generators. There may be one or more magnets to each rope to give the required amount of holding power.

G is the wreck to be raised.

H the same put in dotted lines when raised.

I, I, are balancers hereafter described.

In Fig. 3, K is a lifting chain linked by means of eye L to the bar M. At each end of the bar M a second bar at right angles thereto is linked so as to be able to freely oscillate. To the ends of these two bars 275 four magnets are pivoted so that they can stand at any reasonable angle with the bar. The mode of operating this part is as follows: When the cable sinks with the four magnets attached thereto, each magnet takes hold of the metallic portions of the ship. The ship is not always horizontal. If the forward end be lower than the rear end of the ship, the forward magnets will catch first, but as the cable is lowered, the hinder 30 ones also catch and if the deck or other portion caught be sloping laterally, the two aft magnets catch successively. A reasonable pull is now brought to bear by the crane and the rest of the cable being connected to the 35 magnets along the iron bars each magnet is independently controlled, and by testing these wires, it can be seen at once whether all four magnets hold. If they do not, the current must be cut off, and the cable raised 40 and lowered until they all catch. If the four magnets be arranged in series from a single circuit, the question of whether the magnets catch or not can be quickly settled by divers or by electric light and photograph. Where the wreck is not so deep but that divers can be employed, the divers themselves can drag the magnets about so as to cause each to have a good firm hold.

It will be noticed from the drawing that 45 the pontoons are sufficiently far apart to give thorough stability, and also to enable the wreck to be raised between them, till the top appears on the surface. It will be obvious that two or more of these pontoons 50 can be used to a wreck as one of the pontoons can pull directly upward, and the

other one or two at each side having been first attached to the wreck can pull up somewhat obliquely if required. One, two or more electromagnets can be attached to 5 each rope so as to give the required holding power.

By the plan shown in the drawing, it will be seen that each rope hangs over a large sheave of ample diameter fitted to the cross 10 head of its corresponding hydraulic equalizing ram. From this sheave the rope passes to a suitable winch D which applies the necessary lifting power. The kind of winch which I suggest, is that known as a 15 warping drum, or fleeting, or surging sheave, having a taper or V-shaped tread, around which the lifting rope would make 3 or more turns to give the necessary adhesion. From this fleeting sheave D in the 20 drawing, the tail end of the rope passes to a secondary winch or stock drum E. The latter is driven by a steam engine or electric motor or other suitable power apart from the main lifting engines, the only object of 25 this secondary winch or drum being to take up the slack of the lifting rope, and maintain a constant but slight tension on the tail end of the lifting rope. Incidentally the 30 rope would be kept coiled on this secondary drum E when not in use. Each main lifting rope would of course have its own separate lifting drum and its own secondary storage drum, but a series of these main lifting drums could be mounted on one 35 common shaft either directly or by suitable clutches on shafts running either longitudinally or transversely to the pontoon so that they would all revolve at exactly the same speed, and being all of the same size give 40 exactly the same travel to all the lifting ropes, while at the same time during the fixing, each lifting rope can be attended to, independently of the rest, if required.

All the rams are exactly the same size, 45 and working in similar cylinders and being all connected to the same high pressure water main, would be of such size as to exactly balance or slightly exceed the weight of the ropes and the lifting tension on those 50 ropes when working with a given depth of water. Each ram has a sufficient length of stroke or travel to provide for the maximum rise and fall to be expected from the prevailing working and weather conditions, say 55 about 15 feet, which would thus provide for a maximum variation of about 30 feet in actual lift.

The whole of the hydraulic cylinders would be connected to one common water 60 main with similar connections, and with an accumulator or balancer common to the whole series of mains and connections.

The accumulator or balancer is loaded with a dead weight load of water or metal 65 or with a steam or pressure load, or a com-

bination of these, and if desired more than one accumulator or balancer can be employed, dependent upon the length and number of water mains used. Suitable relief valves are also placed at suitable intervals along the mains to prevent any excess of water pressure and to take up sudden shocks that might arise in actual working. 70

A wreck of known weight calculated as in the water is located by the usual means, and its exact position and orientation carefully ascertained, the pontoon is floated over it, as near as possible parallel with its axis, a tolerably central electro-magnet and ram is then put into operation, the electromagnet 80 is lowered down until it comes in contact with the wreck. If necessary photographic cameras of suitable watertight construction are then lowered over the wreck, together with suitable electric lighting arrangements, 85 in order that photographs can be taken, to show how the wreck is lying, whether deck, beam, or bottom upward, so that suitable provision can be made and the right shaped electromagnets used accordingly. A sufficient number of other electromagnets are successively put down till they grasp the wreck, care being taken by trial lifts that each magnet has got hold of a sufficiently stable part of the wreck to sustain the full 90 load required, say 80 tons, and this goes on until all the electromagnets are fixed. During this operation it may sometimes be required to guide the pontoon somewhat to the windward or current side by means of 95 anchors or the like. The magnets with their corresponding lifting ropes and insulated electric cables are lowered either one by one, or several together, by unwinding their corresponding main hauling drums, and a trial 100 pull equal to the maximum lift required, is made on each rope to insure that its magnet has got a sufficiently good hold on a suitable part of the wreck. The rope is then slackened off for the time being, the electric current being of course still maintained on the magnet though preferably in reduced quantity or strength, until the whole of the magnets are made fast. It will be understood 105 of course that in deep water where the pressure is too great, a diver cannot go down to arrange the fixing of these electromagnets; the actual arrangements will be somewhat in the nature of trial and error, and if 110 a magnet when lowered will not sustain the trial pull, and it is pulled off the wreck, it can be lowered down again and its position 115 slightly altered until the required holding power is attained.

The position of any given magnet can be ascertained if necessary by photography and electric light. When all the magnets are fixed, water is pumped into the whole of the hydraulic cylinders and balancers, 120 so as to raise the rams which carry the lift- 125

ing ropes, and so tighten them up. The travel of the rams is adjusted to about one-half of their run out, say 7 or 8 feet, by arranging a suitable amount of slack on the 5 lifting ropes.

The hydraulic balancer (or balancers if more than one be employed) is also adjusted in a similar manner. When the hydraulic pumps have arrived at this stage, they are 10 stopped, and only sufficient water subsequently added to make up for any leakage or waste that may occur.

The reason for having so many equalizing rams is that the weight shall be distributed 15 over the whole of the electromagnets and ropes equally, the pressure water being brought from the same accumulator or connected accumulators or equivalent device, to all the rams. Another advantage of all 20 the rams being connected is that it allows for the rise and fall of the lifting vessel or pontoon. Spring mechanism can if necessary be introduced in the winches so that the rope can be made to give a little, and allow 25 for excessive strains owing to the rise and fall of the pontoon.

If, while the wreck is being raised, say the bow end of the pontoon were to give a sudden lurch upward owing to the waves on 30 the surface of the water, extra pressure would be at once put upon the rams at the bow end, and lessened pressure upon those at the stern end (owing to the dip of the stern) with the result that the plus pressure water 35 would at once be driven out of the bow cylinders into the rear end cylinders, thus maintaining practically constant pressure on the whole series of rams. For this purpose the water mains should be of ample size 40 to readily allow the water to pass to and fro along the rams and balancers, and thus equalizing the pressure on the rams throughout. The balancing of these pressures is also assisted by the accumulator or balancer 45 already referred to, the weighted ram or rams (if there be more than one) of which will rise up and fall as the pressures vary, while the maximum weight on the balancer 50 governs the maximum strain which can be put on the lifting ropes. This maximum strain on each rope is also controlled by the action of the relief valves, which are provided at suitable intervals along each series 55 of water mains, or it may be on each cylinder. When thus substantially equal pressures on the whole of the lifting ropes are thus secured, the main lifting drums are started in motion, care being taken as already described to insure that they shall all 60 revolve at the same speed so as to provide for equal haulage on each rope; the tailends of the ropes unwind from the lifting winches on to their respective stock drums in the manner already described. Then supposing 65 by any chance, any one rope got wound in

more quickly than the others, owing to its lifting drum being larger in diameter, or driven more quickly than the others, this would put an extra strain on its corresponding ram, which would thus be depressed, 70 and show at once to the men in charge, that this particular drum was, in fact, winding in its rope too quickly. Or, supposing on the other hand, that a magnet slipped, or came off the wreck, or if a rope broke, or 75 any unusual thing happened to lessen the strain on any rope, its equalizing ram would at once shoot out to the length of its full travel, and at once show that something was wrong. Tension chains or other suitable 80 stopping arrangements are provided to prevent a ram being forced completely out of its cylinder, in this case. The position of these equalizing rams, relatively to each other thus forms a kind of barometer, to 85 show how the lifting on each separate rope is progressing. The winding of the ropes now goes on continuously until the wreck is hauled up between the vertical sides of the pontoon, when auxiliary main ropes can be 90 passed immediately under the wreck from one side to the other, and thus permanently secure it to the pontoons. The pontoon with its wreck can then be towed into port, and repaired at leisure, or the holes in the 95 wreck can be plugged up and the water pumped out, and the wreck made self floating before being towed into port.

It is believed that after the wreck has been properly located it will in most instances 100 be a matter of a week or so only to be able to raise it from any reasonable depth, though of course when a very great depth, and consequently there is a great length of lifting ropes, extra time may be employed in maneuvering to get the lifting magnets firmly attached to the wreck at great depths. For very great vessels, such as for instance the "Lusitania", several of these pontoons can be used, one behind the other. 105

It is understood that one or more magnets can be attached to each lifting rope, and if for example, say four or five (or any other number) separate magnets were used, they would be so connected together in a swiveling or equalizing frame, as to form one point of suspension for the lifting rope, as for instance the arrangement in Fig. 3, while allowing freedom of movement to each individual magnet so that it could adjust itself 115 to the shape or contour of the wreck, over which it found itself.

I declare that what I claim is:—

1. In a magnetic lifting apparatus comprising a cable, a supporting bar connected to the cable, transverse bars connected to the supporting bar, and magnets connected to the transverse bars. 125
2. In a magnetic lifting apparatus, comprising a cable, a supporting bar connected to the transverse bars. 130

to the cable, transverse bars pivotally connected to the supporting bar, and magnets connected to transverse bars.

3. In a magnetic lifting apparatus, comprising a cable, a supporting bar connected to the cable, transverse bars pivotally connected to the supporting bar, and magnets pivotally connected to the transverse bars.

4. In a magnetic lifting apparatus, a cable, a supporting bar loosely supported by the cable, transverse bars pivotally con-

nected to the ends of the supporting bars, and magnets pivoted to the transverse bars and having a movement at right angles to the movement of the bars.

15

In witness whereof, I have hereunto signed my name this 23rd day of June 1916, in the presence of two subscribing witnesses.

JOSEPH WALWYN WHITE.
